UNITED STATES PATENT OFFICE.

CHARLES S. GARDINER, OF CHICAGO, ILLINOIS.

MACHINE FOR WELL-BORING AND DRILLING.

SPECIFICATION forming part of Letters Patent No. 403,097, dated May 14, 1889.

Application filed April 12, 1888. Serial No. 270,477. (No model.)

To all whom it may concern:

Be it known that I, CHARLES S. GARDINER, a citizen of the United States, residing at Chicago, in the county of Cook and State of Illinois, have invented certain new and useful Improvements in Machinery for Well-Boring and Rock-Drilling, of which the following is a specification.

My invention relates to machinery designed to operate a rock-drill, or an auger used for well-boring. Such machinery is so constructed that the drilling is effected by a lifting and automatically-tripping device, and the boring by simply disengaging such device from the rest of the machinery and then operating the machinery as before.

My invention is illustrated in the accompanying drawings, in which—

Figure 1 is a side elevation of the rock-drilling and well-boring machinery which constitutes my invention. Fig. 2 is a vertical longitudinal section of the same, taken on the line 1 1 in Fig. 1. Fig. 3 is a detail elevation of the eccentric and eccentric-wheel which operate the drill. Fig. 4 is a detail elevation of the eccentric and eccentric-wheel and the inner end of the windlass with the operating-fingers. Fig. 5 is a vertical section of the upper end of the drill-shaft with the loosening device; and Fig. 6 is a plan section of the machine, taken on the line 2 2 in Fig. 2.

The same letters refer to similar parts throughout the several views.

Referring to the drawings, A is the framework which supports the operative machinery. This is designed to be mounted and secured upon cross-timbers on the trucks of a wagon, so that the machine may be operated on such wagon and may be easily transported from place to place.

A' is a circular trackway, rabbeted on its inner side and furnished with cogs beveled toward their outer ends, whereon the operative machinery revolves when in use.

B B are beams, designed to support the pulley C, by the revolution of which the drill-shaft is lifted. These beams stand on the casting A³, being secured to it by the hinges a. At their tops the beams are fastened together by any suitable means, and secured in

position by the guys a', which guys may be fastened at their lower ends to stakes driven in the ground.

At the center of the trackway A' is the circular casting A², having a vertical opening 55 through it to allow the passage of the drill-shaft D, and having two spokes. The casting A³ has at its center a hub which encircles the central part of the casting A² when in position ready for work. This hub rests on the 60 anti-friction rollers a², journaled on set-screws extending into the ring A⁵ encircling the casting A².

The arms of the casting A³ are secured at their outer ends to the frame A⁴. Levers for 65 the application of power are secured to the frame A⁴ at the points where the arms of the casting A³ meet said frame. Said levers are preferably of wood. They extend horizontally outward from the frame and are fitted with 70 suitable attachments at their outer ends to hitch horses or other draft-animals to for the purpose of operating the machinery. The guys P', extending from the upper ends of the beams B, support the outer ends of the levers. 75

E is a shaft journaled at its outer end in journal-boxes in the frame A⁴ and at its inner end in a socket-bearing in the casting A³.

E' is a windlass revolving on the shaft E. It has on its outer end a collar to fit in the 80 rabbet of the trackway.

E² is a pinion on the outer end of the windlass, beveled toward its inner side. Thus by the action of this bevel and the collar above mentioned the windlass is held securely in 85 its destined course.

On the periphery of the inner end of the windlass are the dovetailed lugs e. On these lugs are secured the dovetailed finger-pieces e'.

F is an eccentric-wheel keyed on the inner 90 end of the shaft E.

F' is an eccentric within which the eccentric-wheel F turns, the eccentric-wheel F being all the time in contact with the eccentric F'. The periphery of the eccentric F' is grooved 95 so as to retain a cord or chain passed over it.

f is a lug on the outer edge of the eccentric F' designed to engage with the finger-pieces e'.

G and G' are respectively a worm and a worm-wheel, the former gearing into the cogs 100

of the latter. The wheel is keyed on the shaft E and is designed to operate the eccentric-wheel F.

It is obvious that by operating the worm G 5 the eccentric-wheel F will be revolved and the eccentric F' raised or lowered. Thus the time that the lug f will be in contact with a finger, e', will be increased or diminished. By the same means the former may be thrown 10 completely beyond the reach of the latter, which is done when the machine is used for boring instead of drilling.

H is a shaft resting in journal-bearings corresponding to those designed for the shaft E.

15 H' is a beveled pinion similar to the pinion E², rigidly secured upon the shaft H.

H² is a gear-wheel rigidly secured to the pinion H' and provided with a collar designed to revolve in the rabbet of the trackway.

20 h is a gear-wheel of half the diameter of the wheel H², engaging with said wheel and keyed on the short shaft h', which revolves in a suitable journal-box mounted on the casting A⁴.

25 H³ is a gear-wheel equal in diameter to the wheel H² and keyed on the shaft h'.

h² is a gear-wheel equal in diameter to the wheel h, engaging with the wheel H³, rigidly secured to the wheel H⁴ and revolving with 30 it on the shaft H.

H⁴ is a balance-wheel loosely mounted on the shaft H, and a set-screw passes through its hub, by tightening which it will be made to revolve when the shaft H revolves. The 35 design of this wheel is to secure steadiness in the action of the machinery. It is obvious that its velocity will be quadrupled by loosening its set-screw and connecting it with the wheel h². When only the velocity of the 40 shaft h is desired, the set-screw is tightened, and the wheels H³ and h are detached from the machinery.

I is a weight having an aperture large enough to allow the drill-shaft to pass up and 45 down through it, and having flanges on opposite sides to travel in the guides I' on the inner sides of the beams B. This weight is designed by its striking force to aid the pulley C in loosening the drill after it has struck 50 a blow. To this end it has the lifting-rods i, which pass up through the cross-head J, to which is secured the cord K, which passes over the pulley C. To regulate the length of the upward stroke of the weight I, the rods i 55 being rigidly secured in the weight are screw-threaded a sufficient length at their upper ends and pass through nuts on either side of the cross-head.

K is a cord secured to the cross-head J, 60 passed up over the pulley C and down and around the hook L, so as to be secured to it. This cord is sufficiently long to extend down to the windlass E', so as to be secured to it in any suitable manner. When not in such 65 use, its surplusage can be wound around a pin secured in the frame-work at any suitable point, as at x in Fig. 1. The cord K' is

secured to the hook L', passed down around the pulley M, pivoted on a shaft secured in the adjacent beam B, and then to the upper 70 angle of the eccentric F', where it is securely fastened. The hooks L and L' are secured to a bar, N, which passes up and down in the guides N', secured to the adjacent beam B. k' is a cord secured to the lower angle of the 75 eccentric F', passing around in the groove in this eccentric, up under the pulley M' to the spring O, to which it is fastened. To the upper end of this spring the cord k² is fastened, and then passes over the pulley M³, secured 80 to the said beam B, and down to the hook L, to which it is fastened.

The operation of the above-described machinery is as follows: If the work to be done is drilling, before starting the machinery the 85 shaft E is turned by actuating the worm-wheel G, so that the eccentric-wheel F will lower the eccentric F' till the lug f on the eccentric will engage with the fingers e'. As the revolution of the machinery proceeds, the 90 pinion E² and the windlass E' will revolve about the shaft E. Thus the lugs e, and with them the fingers e', will be carried around, the latter will engage with the lug f on the eccentric F', and this lug will be carried 95 downward, and along with it the cord K', the hook L', the bar N, the hook L, and the outside part of the cord K. Thus the pulley C will be turned, and the cross-head J, weight I, and drill-shaft D will be lifted. It is obvious that as the weight I, rising, reaches the under part of the head of the drill-shaft, it will, by virtue of its momentum, exert a striking force upward, and will thus aid in loosening the drill. As the finger e' descends, it 100 will pass below the lug f, and thus all the above-described lifting elements will be released, the drill-shaft will drop, and the drill will do its work. When the above release is 105 effected, the spring O will prevent too sudden reaction of the lifting elements. The cord k and its continuation in the spring O, and the cord k', prevent the eccentric F' from reacting too far, holding it so that the lug f will 110 remain at the left (as viewed in Fig. 1) of the longitudinal axis of the beam B. The frequency of the stroke of the drill will be determined by the number of the lugs e that are fitted with the fingers e'. By elevating the eccentric F' so that its lug f will not engage 115 with the fingers e', the machinery can be revolved without actuating the drill. Then the cord k can be detached from the hook L and the part that was coiled around the pin x may be taken down and its end secured to 120 the windlass E', which, as it revolves, will wind the cord around it, and thus lift the drill 125 continuously. This will be found convenient, especially when boring deep wells.

It is obvious that when the above adjustment of the eccentric F' has been made the machinery will be ready for boring when an auger has been substituted for the drill.

Having now described my invention, what I

claim as new, and desire to secure by Letters Patent, is—

1. In a rock-drilling and well-boring machine, the combination of a vertical pivot-casting with a central vertical aperture, a horizontal circular cogged trackway, a hub-casting, with two spokes to revolve about said pivot, a frame bolted to the ends of said spokes, beams secured upon said hub by 10 hinges and fastened together at their other ends by a cap-piece with a central aperture, a pulley secured near the end of one of said beams farthest from the hub, a shaft for drill or auger, a cord secured to said shaft and passing over said pulley, a windlass secured in said frame and furnished with lugs at right angles to its inner end, on which fingers may be fixed, an eccentric furnished with a lug at right angles to said lugs and fingers, and connected with the drill-shaft by cords passing over said pulley, an eccentric-wheel within said eccentric, and levers for the application of power, all secured upon the trucks of a wagon, for the purposes stated.
2. In a rock-drilling and well-boring machine, substantially as described, the combination of the hollow pivot A^2 , the ring A^5 encircling it, the circular trackway A' , the hub A^3 , provided with two spokes, the frame A^4 , bolted to the ends of said spokes, the horizontal shafts E and H , journaled in said frame and hub, the beveled pinions E^2 and H' , secured on shaft so as to revolve in said trackway, the beams B , hinged upon said hub and held together at their ends by a cap-piece, and provided with the guides I' on their inner faces, the guy-ropes P and a' , secured to said cap-piece, the drill and auger shaft D , the weight I , provided with flanges to move in 30 said guides, the cross-head J , the screw-threaded rods i , secured in said weight and in said cross-head, and levers for the application of power secured in the frame A^4 , all secured upon the trucks of a wagon, as and for 35 the purposes stated.
3. In a well-boring and rock-drilling machine, substantially as described, the combination of the eccentric-wheel F , keyed on the shaft E , against the inner end of the windlass E' , the eccentric F' , grooved on its outer edge and having at its upper corner the lug f , extending at right angles to its outer face, the windlass E' , provided with the lugs e , extending from its inner end at right angles to its 40 length, the finger-pieces e' , fitting on said lugs, the spring O , the rod N , moving in guides secured to the beam B , and furnished with the hooks L and L' , the cord k , secured to the

lower corner of said eccentric and passing about it and under said pulley and secured 60 to the lower end of said spring, the pulleys M , M' , and M^3 , pivoted on said beam, the cord K' , secured to the upper corner of said eccentric, passing about the pulley M and secured to the hook L' , the cord k' , secured to the upper end of said spring and passing over the pulley M^3 and secured to the hook L , and the cord K , secured to the cross-head J , passing over the pulley C , and secured to the hook L , as and for the purposes stated. 70

4. In a rock-drilling and well-boring machine, substantially as described, the combination of the anti-friction rollers a^2 , the ring A^5 , having said rollers pivoted to it at its periphery, the pivot-casting A^2 , furnishing a 75 trackway for said rollers, and the hub-casting A^3 , resting on said rollers, substantially as stated.

5. In a rock-drilling and well-boring machine, substantially as described, the weight 80 I , furnished with flanges to move in guides I' on the inner sides of the beams B , having an opening for the passage of the drill and auger shaft D , fitted with the rods i , rigidly secured to its upper part, in combination with the 85 cross-head J above the head of said shaft, as and for the purpose stated.

6. In a well-boring and rock-drilling machine, substantially as described, the combination of the pinion H' , rigidly secured on the 90 shaft H , the gear-wheel H^2 , secured to the pinion H' , the gear-wheel h , keyed on the shaft h' , and having a diameter equal to an aliquot part of the diameter of wheel H^2 , the gear-wheel H^3 , keyed on said shaft and being of 95 equal diameter with wheel H^2 , the gear-wheel h^2 , pivoted on the shaft H and having a diameter equal to that of wheel h , the balance-wheel H^4 , rigid with the wheel h^2 and pivoted on the shaft H , and having its hub pierced 100 with a hole for a set-screw, as and for the purposes specified.

7. In a well-boring and rock-drilling machine, substantially as described, the combination of the shaft E , the worm G , the worm-wheel G' , the eccentric-wheel F , the grooved eccentric F' , having at its outer edge the lug f , the windlass E' , having on the periphery of its inner end the lugs e , and the finger-pieces e' , made to fit upon said lugs, as and for the 110 purpose specified.
